UNITED STATES PATENT OFFICE.

LOUIS BAUER, OF NEW YORK, N. Y., ASSIGNOR OF ONE-THIRD TO HENRY J. BAUER
AND ONE-THIRD TO FREDERICK TURNER, BOTH OF NEW YORK, N. Y.

MEANS FOR MOUNTING MULTIGRAPH PLATES.

Application filed March 15, 1923. Serial No. 625,246.

To all whom it may concern:

Be it known that I, LOUIS BAUER, a citizen of the United States, and residing at New York, in the county of New York and State of New York, have invented certain new and useful Improvements in Means for Mounting Multigraph Plates, of which the following is a specification, such as will enable those skilled in the art to which it applies to make and use the same.

This invention relates to multigraph plates and particularly to means for mounting or supporting said plates in connection with suitable supports, such for example as cylinders or drums having a plurality of spaced longitudinal slots which are substantially T-shaped in form in cross section; and the object of the invention is to provide a simple, effective and yet strong and durable means for mounting multigraph plates in connection with supports, and for retaining said plates on said supports substantially as hereinafter described and claimed.

The invention is fully disclosed in the following specification, of which the accompanying drawing forms a part in which the separate parts of my improvement are designated by suitable reference characters in each of the views, and in which:

Fig. 1 is a transverse sectional view through a part of a cylinder or drum showing a plate mounted thereon with one form of my improved attaching means or devices.

Fig. 2 is a perspective view of the back of a multigraph plate showing a number of my improved devices mounted in connection therewith.

Fig. 3 is a partial section on the line 3—3 of Fig. 1.

Fig. 4 is a perspective view of one of the devices which I employ in the construction shown in Figs. 1, 2 and 3.

Fig. 5 is a sectional detail view showing a modified form of attaching device; and,

Fig. 6 is a perspective view of another form of attaching device with part of the construction shown in section.

In Figs. 1 and 3 of the drawing, I have shown at 10 a drum or cylinder, the periph-

ery of which is provided with circumferentially spaced longitudinal slots 11 which are substantially T-shaped in form in cross section; and at 12 I have shown a multigraph plate having a suitable projecting printing surface 13, and in practice, I provide a number of attaching or mounting devices 14, one of which is shown in detail in Fig. 4 of the drawing for mounting and supporting the plate 12 upon the periphery of the cylinder 10 as shown in Figs. 1 and 3 of the drawing.

The attaching device 14 is in the form of a brad and is composed of a strip of sheet metal fashioned to form an elongated, narrow crosshead 15, and a shank 16 extending at right angles from the central face of the crosshead 15, and twisted as shown at 17 to extend the flat faces thereof in a plane longitudinally with the plane of the crosshead, and the shank 16 is composed of separate members which are adapted to be parted and folded laterally to form retaining flanges 18.

In carrying my invention into effect and in the use and application of the attaching device 14, the plate 12 shown in Fig. 2 of the drawing is provided with two sets of elongated apertures 19, each set of apertures being arranged in common longitudinal alignment on the plate 12 and being located in such manner as to not interfere with the type faces 13 of the plate, and in attaching the devices 14 to the plate, two of these devices are placed in one of the recesses 11 in the cylinder 10, and the other two in another recess, it being understood that the separate sets of apertures 19 are cut in the plate 12 to register with the recesses 11 above referred to, after which the shanks 16, being folded, are passed through the apertures 19 and the plate 12 is placed upon the cylinder 10 after which the shanks 16 are bent to form the flanges 18 and if desired a metal solder or the like 20 is applied to the plate around the flanges 18 to retain the same in position. In the above operation, it will be understood that the crossheads 15 of the devices 14 are placed in the T-shaped recesses 11 and said crossheads extend longitudinally of said recesses.

The above method of attaching and mounting the plate 12 in connection with the cylinder may be readily accomplished without great skill or care upon the part of the operator and effects a material saving in the accomplishment of the desired result over methods which are now practiced, one of the most common of which consists in sweating, soldering or otherwise mounting elongated metal strips substantially T-shaped in cross section to the back faces of plates of the class under consideration and in accomplishing this result a torch is used for securing the strips to the plate, which many times unless great care is taken, would destroy the plate due to overheating said plate. In the present method of procedure, it requires an operator of the greatest skill to accomplish the desired result, and these operators are paid high salaries, while with my method of procedure, the desired result may be accomplished in a simple, effective and economical manner.

In Fig. 5 of the drawing, I have shown another method of carrying my invention into effect, in which I substitute for the devices 14 cylindrical bodies 21 having enlarged heads 22 and reduced shanks 23. The heads 22 are adapted to fit in the grooves or recesses 11, while the reduced shanks 23 are passed through circular apertures 24 in the plate 12, and said reduced shanks are spun or headed as shown at 25 to retain the body 21 in connection with the plate 12. If desired, the body or bodies 21 may be secured in position by sweating or soldering.

In Fig. 6 of the drawing, I have shown another modification in which elongated members 26 are mounted in elongated apertures 19 similar to the apertures 19 shown in the plate 12 of Fig. 2 and the members 26 are provided with enlarged heads 27 adapted to fit in the recesses 11 as will be apparent, and the shanks of the members 26 are preferably split as shown at 28 to form separate parts 29 which are adapted to be bent laterally after they have passed through the plate 12, and the parts 29 may be retained against displacement by punching the metal thereof into the plate 12 as shown at 30, or if desired the parts 29 may be soldered to the plate 12 as shown in Fig. 1 of the drawing. It will be understood that the showing of the several attaching devices 14, 21 and 26 are exaggerated in the accompanying drawing for the purpose of clearly illustrating the invention, and in practice, these members are comparatively small and are of such size as to fit within the grooves 11 in standard cylinders or drums 10.

From the foregoing, it will be apparent that the distinctive feature of my invention consists in mounting in connection with a printing plate or a plate having a print-

ing surface, two or more members having enlarged heads spaced a predetermined distance from the back of said plate for mounting and retaining the plate on a suitable support. While I have shown certain details of construction for carrying my invention into effect, it will be understood that I am not necessarily limited to these details and various changes in and modifications of the construction herein described and claimed may be made within the scope of the appended claims without departing from the spirit of my invention or sacrificing its advantages.

Having fully described my invention, what I claim as new and desire to secure by Letters Patent, is:

1. In a printing plate, means for mounting and retaining said plate in connection with a cylinder comprising substantially T-shaped members, the shanks of said members being adapted to be passed through apertures in said plate at spaced intervals, and the shanks of said members being fashioned to retain said members in connection with said plate with the crossheads of said members positioned at a predetermined distance from the rear face of the plate.

2. In a printing plate, means for mounting and retaining said plate in connection with a cylinder comprising substantially T-shaped members, the shanks of said members being adapted to be passed through apertures in said plate at spaced intervals, the shanks of said members being fashioned to retain said members in connection with said plate with the crossheads of said members positioned at a predetermined distance from the rear face of the plate, and means for permanently retaining said members in connection with said plate.

3. A device for mounting a printing plate in connection with a cylinder comprising a substantially T-shaped body fashioned from sheet metal and the shank of said body being adapted to be fashioned to retain the same in connection with a printing plate.

4. A device for mounting a printing plate in connection with a cylinder comprising a substantially T-shaped body, and the shank of said body being composed of separate members adapted to be extended laterally to retain said body in connection with a printing plate.

5. A device for mounting a printing plate in connection with a cylinder comprising a substantially T-shaped body formed from a strip of sheet metal bent centrally upon itself to form the crosshead of said body, the free ends of said strip depending from said crosshead substantially centrally thereof and being in juxtaposition to form the shank of said body and the separate members of said shank adjacent the free end thereof being adapted to be bent laterally

at right angles to the remainder of the shank in securing the body to a printing plate.

6. A mounting device of the class described formed from a strip of sheet metal, the central portion of which is fashioned to form a crosshead of two-ply thickness, and the free end portions of said strip be-

ing brought together and depending from the central portion of the crosshead to form 10 a shank, and said shank being twisted at right angles adjacent to the crosshead.

In testimony that I claim the foregoing as my invention I have signed my name this 12th day of March, 1923.

LOUIS BAUER.
